UNITED STATES PATENT OFFICE.

WILLIAM G. CHAPMAN, OF HUNTINGTON, WEST VIRGINIA, ASSIGNOR OF ONE-HALF TO
THOMAS J. FEUGATE, OF HUNTINGTON, WEST VIRGINIA.

ELECTRIC GAS-LIGHTER.

1,192,863.

Specification of Letters Patent.

Patented Aug. 1, 1916.

Application filed April 8, 1916. Serial No. 89,880.

To all whom it may concern:

Be it known that I, WILLIAM G. CHAPMAN, a citizen of the United States, residing at Huntington, in the county of Cabell 5 and State of West Virginia, have invented new and useful Improvements in Electric Gas-Lighters, of which the following is a specification.

This invention relates to an electric gas 10 lighter and has for its primary object to provide a device of this character in which the sparking element may be readily renewed. An object of the invention is the manner of mounting the electrodes so that 15 it is impossible for the user to be given a shock.

With these and other objects in view, the invention consists in the construction, combination and arrangement of parts as will 20 be hereinafter more fully described, illustrated in the accompanying drawing and pointed out in the claims hereunto appended.

In the drawing:—Figure 1 is a side elevation of the device. Fig. 2 is a longitudinal section view of the device. Fig. 3 is a 25 diagrammatic view of the wiring.

Referring to the drawing, the numeral 1 designates a tube of insulating material in 30 one end of which is mounted the insulating plug 2 supporting a pair of electrodes 3 in spaced relation. The electrodes 3 are of such a length relative to the plug that the ends project beyond the plug so as to form 35 arcing portions 4 and end portions 5 adapted to be connected to a circuit to be described later. Having screw threaded engagement with the end of the tube or frictionally held thereupon is a clamping ring 40 6 adapted to hold the plug 2 within the tube. Frictionally coöperating with the ring 6 is a cap 7 adapted to protect the arcing portions 4 in the idle periods of the device. The opposite end of the tube has 45 secured thereto a handle 8 through which and the tube 1 pass plungers 9 and 10, the former controlling a switch 12, the latter controlling a switch 11.

The switch 11 controls the continuity of 50 a circuit 13 including the electrodes 3 source

of current 14 and the induction coil 15, while the switch 12 controls the continuity of a circuit 16 that includes an electric bulb 17 supported by the tube 1 that receives current from the source 14. From the foregoing description it will be seen that depressing the plunger 9 will cause the bulb 17 to be energized independent of the remaining elements; whereas depressing the plunger 10 will cause a spark to jump across 60 the electrodes 3 for igniting the gas.

At this point, I wish to call attention to the fact that the plungers 9 and 10 are so associated as to be simultaneously depressed for energizing the bulb 17 and causing the 65 spark to jump across the electrodes 3.

From the foregoing description taken in connection with the accompanying drawing, it should be apparent that I provide a device which is admirably adapted for the 70 purpose for which it is intended, that the device is simple, durable and efficient of construction and that the device may be manufactured and sold at a comparatively 75 low cost.

What I claim is:—

1. An electric gas lighter comprising a tube, a handle mounted on the tube, a plug mounted at one end of the tube, a pair of electrodes supported in spaced relation in 80 said plug, and means for passing a spark across the electrodes, said means including a push button having the slidable member mounted in both the handle and tube.

2. An electric gas lighter comprising a 85 tube, a handle mounted on the tube, a plug mounted at one end of the tube, a pair of electrodes supported in spaced relation in said plug, means for passing a spark across the electrodes, said means including a push 90 button having the slidable member mounted in both the handle and tube, and a ring mounted on one end of the tube and clamping said plug within the tube.

In testimony whereof I affix my signature 95 in presence of two witnesses.

WILLIAM G. CHAPMAN.
